UNITED STATES PATENT OFFICE.

GODFREY S. MAHN, OF PHILADELPHIA, PENNSYLVANIA.

DESIGN FOR A CIGAR-PROTECTOR.

43,150.

Specification for Design.

Patented Oct. 15, 1912.

Application filed March 15, 1912. Serial No. 684,002. Term of patent 14 years.

To all whom it may concern:

Be it known that I, GODFREY S. MAHN, a citizen of the United States, and residing at the city of Philadelphia, in the county of Philadelphia and State of Pennsylvania, have invented a new, original, and ornamental Design for a Cigar-Protector, of which the following is a specification, reference being had to the accompanying drawings, forming part hereof, in which—

Figure 1, is a plan view enlarged, of a beaded cigar protector; and Fig. 2, is a front elevational view, showing the peculiar formation of the beaded tapering extremital portion and round beaded slotted wall of the extremity of said protector, as disclosing in these defined features the design arrangement of the same.

I claim:—

The ornamental design for a cigar protector, as shown and described.

GODFREY S. MAHN.
